UNITED STATES PATENT OFFICE.

JOZSEF MICHKI, OF TERRE HAUTE, INDIANA.

COMBINATION-TOOL FOR SHOEMAKERS.

1,297,386.

Specification of Letters Patent. Patented Mar. 18, 1919.

Application filed May 24, 1918. Serial No. 236,421.

To all whom it may concern:

Be it known that I, JOZSEF MICHKI, a subject of the King of Hungary, residing at Terre Haute, in the county of Vigo and State of Indiana, have invented new and useful Improvements in Combination-Tools for Shoemakers, of which the following is a specification.

This invention relates to combination tools, and the principal object of the same is to combine with a hammer various other important tools used in the art of shoe-making and repairing, the combination tool being designed primarily for use in connection with my novel cobbler's kit for which application for Letters Patent was filed May 24, 1918, Serial No. 236,422.

With the foregoing object and others in view, the invention resides in the details of construction and in the arrangement and combination of parts hereinafter described, and shown in the accompanying drawings, forming a material part of this specification, and in which:

25 Figure 1 is a view in side elevation of the combination tool;

Fig. 2 is a similar view, showing the parts detached but in proper relative position;

30 Fig. 3 is an enlarged cross-sectional view, taken approximately in the direction of the line 3—3 of Fig. 2; and

Fig. 4 is a detail view, showing a modified form of the striking head.

Referring more particularly to the accompanying drawings, the numeral 5 is employed to denote a handle, made preferably of metal, and formed at one end with an integral transversely extending tubular holding head 6 and at the opposite end with 40 an enlarged hollow portion 7 having a series of transversely inclined openings 8, designed to lessen the weight of the handle and at the same time to provide means for safe-guarding against any slipping of the hand 45 when the handle is clasped in use.

Threaded into the interior of the enlarged portion 7 is the reduced end 9 of the handle portion 10, which is designed to provide an extension of the said enlarged portion 7, the 50 same being also formed with similar gripping openings 8. Secured within the extension 10 so as to project centrally from the reduced end 9, is a shoemaker's knife 11,

which, when the parts are assembled, is enclosed within the enlarged portion 7. Extension portion 10 tapers to a flat end 12, where it is provided with a beveled V-shaped notch 13, adapted for use in withdrawing nails and in other capacities.

Engaged within the holding head 6 is the reduced end 14 of the striking head 15, which is expanded to provide an exterior-annular shoulder 16 adapted to abut the said head 6, so as to effect a firm engagement against relative movement when blows are struck. Set screws as 16' are employed to connect the holding head 6 with the reduced end 14. Beyond its flat end 17, the striking head 15 is made tubular throughout.

Threaded within the end 14 is the reduced end 18 of another striking head 19, which is enlarged to provide an annular shoulder 20 to abut the opposite end of the holding head 6, in order as before to effect a rigid engagement for striking purposes. This head 19 is also formed with an intermediate portion 21 of sufficient size to engage the interior of the holding head 6, the annular edge thereof 22 abutting as before against the end 14 of the first striking head. Carried by the striking head 19 so as to project from the reduced end 18 thereof, is an awl 23 for use in piercing leather, and which, when the parts are assembled, is 85 enclosed by the striking head 15.

Instead of making both heads 15 and 19 with flat striking ends, one of them may be formed with a rounded striking end 24, as shown in Fig. 4, adapted to be used in addition to driving nails, as a buff by which to smooth the edges or surfaces of the leather in a manner well-known in the art of shoe-making.

Having thus described my invention, what I claim is:

1. A tool for shoemakers comprising, in combination, a handle formed at one end with a transversely extending tubular holding head, a striking head removably engaged with one end of said holding head, and a second striking head removably engaged with the opposite end thereof and provided with a reduced portion removably engaged with said first striking head.

2. A tool for shoemakers comprising, in combination, a handle formed at one end

with a transversely extending tubular holding head, a hollow striking head removably secured at one end of said tubular holding head, the striking end thereof being rounded and adapted to serve as a buff, and a second striking head removably engaged in the

opposite end of said holding head and having a projecting portion threaded into said first striking head.

In testimony whereof I have signed my name to this specification.

JOZSEF MICHKI.
